UNITED STATES PATENT OFFICE.

ZENAS P. CANDEE, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

POWER PRESS.

Application filed May 1, 1925. Serial No. 27,214.

This invention relates to a new and improved power press and its structure and operation is especially adapted, although not limited thereto, for that type of press where-
5 in two dies are brought together under great pressure and the alignment of the dies should be exact.

It is the object of this invention, among other things, to produce a press wherein the
10 gate is connected with members which have a bearing in a solid frame both above and below that portion of the gate with which the tools are connected and in the attainment of these objects, as well as others, to
15 provide a mechanism that will be composed of a limited number of parts so arranged as to be readily accessible for adjustment, etc., and will have great rigidity when assembled.
20 The improvements in the details and arrangement of parts will be apparent from an inspection of the accompanying drawings in connection with the description herein-
after contained.

25 Referring to the drawings, in which like numerals of reference designate like parts in the several figures:

Figure 1 is a front elevation of my im-
proved power press, with some of the parts
30 thereof shown in section;

Figure 2 is a side elevation thereof;

Figure 3 is a sectional elevation thereof taken generally upon line 3—3 of Figure 1;

Figure 4 is a transverse sectional plan
35 view thereof, the parts in section being taken generally upon line 4—4 of Figure 1;

Figure 5 is an enlarged detail sectional plan view of one of the rod bearings;

Figure 6 is a front elevation of another
40 form of my improved die press having two rods instead of four; as shown in the type of press illustrated in the preceding views;

Figure 7 is a sectional elevation thereof, taken generally upon line 7—7 of Figure 6;
45 and

Figure 8 is a transverse sectional view, taken generally upon line 8—8 of Figure 6.

In the drawings, 10 designates the frame of the press that is shown as supported upon the legs 11, as is usual.
50

This frame is preferably constructed with two uprights 12, which extend between the bed 23 and the head portions 13, which are

joined at their upper ends by the cap 14, secured thereto by bolts 15.

55

Journaled within the split bearings 16, in the frame, is a crank shaft 17, upon the crank 18 of which is the split sleeve 19, to which are clamped the companion connec-
60 tions 20, that are secured at their lower ends to the gate block 21 by means of the tapered pins 22.

Within the bed 23 and the head portion 13, are a plurality of split rod bearings 24 which are arranged in pairs with the axes of the bearings in the bed coincident with those of the bearings in the head. These rod bearings as shown are conical in form and pref-
65 erably provided with slots 25 in their outside wall which do not extend to the bore of the bearing and a slot 26 which extends entirely through one wall of the bearing from the exterior to the bore thereof. These rod bear-
70 ings are adjustably secured by the nuts 27 threaded upon opposite ends thereof and whereby their relative axial position may be
75 varied and the diameter of the bore varied to a limited degree so as to insure an exact bearing surface for the guides 28, which may be rods, as shown, or other shapes and
80 forms, as may seem desirable, movable there-
in and to take up any lost motion that may develop and disarrange the exact alignment of the operating tools. The upper end of each of these bearings is covered by a cap 85 29, within which is the packing 30.

A plate 31 of fiber or similar material placed within each of the slots 26, not only prevents the closing of the bearings too tightly on the rod, but oil from the bearings 90 from running down the outside of the rods 28.

The gate 32 is provided at each corner with the cylindrical portions 33 through which project the rods 28, that are secured 95 therein by the bolts 34, which pass, through the integral lugs 35, between which is the filling plate 37 of fiber or similar material within the slot 36.

Upon the bed 23 is a die block 38 having 100 tools 39 of any desired form or structure therein, and secured to the gate opposite the die block is a holder 40 or the like, having a punch 41 fixed therein.

The tools as shown herein are merely for 105 the purpose of illustrating the position

thereof, as the function, shape and form thereof are immaterial so far as this invention is concerned. The tools may be for embossing, piercing, drawing, or for any other desired purpose.

A vertical reciprocatory movement is given the gate from the crank shaft 17 in the usual manner, during which time the rods 28 move through and are supported by 10 the bearings 24.

By this construction the gate is guided by the rods, the bearings of which are in a solid frame, both above and below the operating faces of the tools, thus providing a 15 very rigid structure especially desirable with a combination of blanking and embossing or stamping tools, and at the same time are accessible both for installation, operation and removal.

20 In some cases it is desirable that the weight of the gate, rods and parts connected therewith, should be taken off the crank shaft, which results in a smoother running machine. The mechanism for accomplishing this purpose, as herein shown, comprises the rod 42 that is fixed in the upper end of each of the rods 28 and having a collar 43 thereon, between which and the cap 29 is a coil spring 44, the tension of 30 which may be varied through the nuts 45. Each of these springs is enclosed within a tube 46.

In Figures 1 to 4, inclusive, the structure shown is designed for a power press having 35 four rods 28. A two rod machine or other multiple of rods may be used with equal advantage. In Figures 6, 7, and 8 is illustrated a type of press wherein there are only two such rods, but the parts adjacent 40 to the rods are the same in both cases.

In this latter form, the head portion 49 projects forward from the uprights 50 and is connected with the bed 23 by the rods 51. The gate 47 in this type of press is 45 slightly modified to provide for the two-rod type, the cylindrical portions 48 thereof being in rear of the tools and extending above and below the corners thereof as in the other type. This gate is actuated from the crank 50 shaft 52 through the connection 53. Otherwise the construction and operation of the mechanism is substantially the same.

There are minor changes and alterations 55 that may be made within my invention, aside from those suggested, and I would therefore have it understood that I do not limit myself to the exact construction herein shown and described, but claim all that falls fairly within the spirit and scope of the appended 60 claims.

Having described my invention, what I claim as new and desire to secure by Letters Patent, is:

1. In a power press, a frame having a bed 65 and a head located above the bed in spaced

relation thereto, bearings carried by the head, bearings carried by the bed and alined with the respective bearings of the head, a gate between the bed and head, a plurality of guide rods, and means to fixedly secure 70 the guide rods to the gate intermediate the ends of the rods, the rods having their ends projecting above and below the gate and being movable in the respective bearings.

2. In a power press, a frame having a bed 75 and a head located above the bed in spaced relation thereto, bearings carried by the head, bearings carried by the bed and alined with the respective bearings of the head, a gate between the bed and head, a plurality 80 of guide rods, means to fixedly secure the guide rods to the gate intermediate the ends of the rods, the rods having their ends projecting above and below the gate and being movable in the respective bearings, and 85 means to effect adjustment of each of the bearings so as to accurately aline same with respect to the guide rods.

3. In a power press, a frame having a bed 90 and a head located above the bed in spaced relation thereto, bearings carried by the head, bearings carried by the bed and alined with the respective bearings of the head, a gate between the bed and head, a plurality 95 of guide rods, means to fixedly secure the guide rods to the gate intermediate the ends of the rods, the rods having their ends projecting above and below the gate and being movable in the respective bearings, and means to enable adjustment of the diameters 100 of the bores of the bearings.

4. In a power press, a frame having a bed and a head located above the bed in spaced relation thereto, bearings carried by the head, bearings carried by the bed and alined with the respective bearings of the head, a gate between the bed and head, a plurality 105 of guide rods, means to fixedly secure the guide rods to the gate intermediate the ends of the rods, the rods having their ends projecting above and below the gate and being movable in the respective bearings, and 110 spring means connected to each of the guide rods to assist movement thereof in one direction.

5. In a power press, a frame having a bed and a head located above the bed in spaced relation thereto, bearings carried by the head, bearings carried by the bed and alined with the respective bearings of the head, a gate between the bed and head, a plurality 115 of guide rods, split portions carried by the gate and formed to receive intermediate portions of the guide rods, and means to secure the split portions to the rods so as to fixedly 120 secure the latter to the gate, said rods having their ends extending above and below the gate and being received in the respective 125 bearings.

6. In a power press, a frame having a bed 130

and a head located above the bed in spaced relation thereto, bearings carried by the head, bearings carried by the bed and alined with the respective bearings of the head, a plurality of guide rods, cylindrical members on the gate formed to receive intermediate parts of the rods and projecting downwardly from the gate and toward the bed, and means to fixedly secure the rods in the members, the rods having their ends extending above and below the gate and being received in the respective bearings.

7. In a power press, a frame having a bed and a head spaced above the bed, alined bearings carried by the bed and by the head, a gate between the bed and head, downwardly extending split members carried by the gate, guide rods having intermediate portions thereof received in the members, and means to clamp the split members to the rods so as to fixedly secure the latter to the gate, the rods having their ends projecting above and below the gate and movably received in the bearings.

8. In a power press, a frame having a bed and a head located above the bed in spaced relation thereto, bearings carried by the head, bearings carried by the bed and alined with the respective bearings of the head, a gate between the bed and head, and a plurality of guides fixedly secured to the gate having parts projecting above and below the gate and being movable in the respective bearings.

9. In a power press, a frame having a bed and a head located above the bed in spaced relation thereto, bearings carried by the head, bearings carried by the bed and alined with the respective bearings of the head, a gate between the bed and head, a plurality of guides fixedly secured to the gate having parts projecting above and below the gate and being movable in the respective bearings, and means to effect adjustment of each of the bearings so as to accurately aline same with respect to the guide rods.

10. A power press having a frame with a bed and a head portion opposite to each other and an open space therebetween, a gate movably mounted between the head and the bed; a plurality of guides fixed to the gate and projecting above and below the same and through the said bed and head portions; an extension rod connected with each of said guides; a collar thereon; and a spring between the guide and collar.

11. In combination with the frame of a press, guides, a gate associated with the guides, and a bearing for each of the guides, having a conical exterior, a slot extending through the wall thereof into the bore of the bearings, and means for moving the endwise position of the bearings whereby the diameter of said bore may be varied to a limited degree.

In testimony whereof, I have hereunto affixed my signature.

ZENAS P. CANDEE.
